United States Patent

Des. 239,543
Patented Apr. 13, 1976

239,543

SWINGING GATE

Frank Kratky, Bellvue, Colo., assignor to Westguard
Products, Inc., Fort Collins, Colo.

Filed Mar. 18, 1974, Ser. No. 451,791

Term of patent 14 years

Int. Cl. D25—02

U.S. Cl. D28—1 B

Fig. 4

Fig. 3

FIG. 1 is a perspective view of a swinging gate showing my new design;

FIG. 2 is a front elevational view thereof;

FIG. 3 is a side elevational view taken from the left of FIG. 2; and

FIG. 4 is a top plan view thereof.

I claim:

The ornamental design for a swinging gate, as shown and described.
